(57) **CLAIM**

The ornamental design for a door supporting device, as shown and described.

DESCRIPTION

FIG. 1 is a front view of the door supporting device; FIG. 2 is a rear view of the door supporting device of FIG. 1;

FIG. 3 is a right side view of the door supporting device of FIG. 1;

FIG. 4 is a left side view of the door supporting device of FIG. 1;

FIG. 5 is a top plan view of the door supporting device of FIG. 1;

FIG. 6 is a bottom plan view of the door supporting device of FIG. 1;

FIG. 7 is a longitudinal sectional view of the door supporting device taken along line 7—7 in FIG. 1;

FIG. 8 is an enlarged cross sectional view of the door supporting device taken along line 8—8 in FIG. 1;

FIG. 9 is an enlarged cross sectional view of the door supporting device taken along line 9—9 in FIG. 1;

FIG. 10 is a front view of the door supporting device of FIG. 1, with the adjusting plate having been rotated clockwise;

FIG. 11 is a front view of the door supporting device of FIG. 1, with the adjusting plate having been rotated counterclockwise;

FIG. 12 is a front view of the door supporting device of FIG. 1, with the stopper having been rotated;

FIG. 13 is a top plan view of the door supporting device of FIG. 1 in position of use shown on a reduced scale;

FIG. 14 is a right side view of FIG. 13; and,

FIG. 15 is a perspective view of the door supporting device of FIG. 1.

The broken lines showing environment in the drawings are for illustrative purposes only and form no part of the claimed design.
